CLAIM

The ornamental design for a display screen or portion thereof with graphical user interface, as shown and described.

DESCRIPTION

FIG. 1 is a front view of a first embodiment of a display screen or portion thereof with graphical user interface showing our new design;

FIG. 2 is a front view of a second embodiment of a display screen or portion thereof with graphical user interface showing our new design;

FIG. 3 is a front view of a third embodiment of a display screen or portion thereof with graphical user interface showing our new design; and,

FIG. 4 is a front view of a fourth embodiment of a display screen or portion thereof with graphical user interface showing our new design.

The outermost broken lines in the figures show a display screen or portion thereof. The remaining broken lines in the figures show portions of the graphical user interface. None of the broken lines form part of the claimed design.
